DESIGN FOR A TABLE CASTER

Louis Chazin, Brooklyn, N. Y.

Application October 29, 1945, Serial No. 123,279

Term of patent 7 years

(Cl. D44—24)

To all whom it may concern:

Be it known that I, Louis Chazin, a citizen of the United States, residing at Brooklyn, in the county of Kings and State of New York, have invented a new, original, and ornamental Design for a Table Caster, of which the following is a specification, reference being had to the accompanying drawings, forming part thereof.

Fig. 1 is a front elevational view of a table caster, showing my new design.

Fig. 2 is a top plan view thereof.

Fig. 3 is a rear elevational view thereof.

Fig. 4 is a perspective view showing the device as it would appear from above and to the left of the showing in Fig. 1.

Fig. 5 is a perspective view of the table caster showing the side opposite to that shown in Fig. 4.

The dominant features of the design reside in the portions shown in full lines.

I claim:

The ornamental design for a table caster, substantially as shown and described.

LOUIS CHAZIN.
